PAPER MILK BOTTLE

Herald T. Snyder, Seattle, Wash., assignor of one-half to Henry H. Judson, Seattle, Wash.

Application June 11, 1937, Serial No. 147,741

6 Claims. (Cl. 229—37)

My invention relates to the art of paper containers suitable for the transportation, storage, or vending of granular or liquid products. Because, however, of its special adaptability for liquids, I prefer to term my invention a paper milk bottle.

The general public has already accepted as desirable the single service paper milk bottle. It has many practical characteristics; the principal one, because the container is made from paper, is the elimination of the constant threat of small particles being broken from a glass bottle and swallowed as the contents are consumed; it provides a very marked degree of sanitation in that the bottle can be used only once, and that by the person who receives the milk; it cannot have been mistreated by former users; it is not subject to contamination by being left on porches and the like.

To date it has appeared impractical to supplant the present glass milk bottle which may be used according to reliable statistics about seven times, on an average, before they are unserviceable through breakage.

The various paper bottles that have been offered to the public have not admitted of sufficiently economical manufacture and handling to compete favorably with the glass bottle. In my present design, however, I believe that I have overcome the deficiency of the various paper bottles that have been used to date and have preserved in my invention all of the desirable characteristics so much desired by the trade.

In my present construction I provide a bottle that is made from a single sheet of paper so that it may be shipped flat and can be assembled very economically without the use of metal stiffening devices or special closure members. I obtain the desired degree of stiffness by forming the bottom and top of my bottle of two or more thicknesses of paper so that they tend to reinforce each other and provide a laminated cross-section that produces a degree of stiffness that is essential to this form of construction.

Further, without wastage of paper, I provide a convenient means of carrying my bottle, or for hanging it as on a doorknob.

Another advantage of my present construction is that it admits for certain uses, as in the transportation of milk, the provision of a cream line window so that the one objection the housewife may have to a paper bottle in contradistinction to the glass, is satisfactorily overcome. This window is formed with reinforcing, which again is made without wastage, by merely utilizing a

tab of the paper which would otherwise serve no purpose.

Still another advantage of my present design is in having trapezoidal sides that present a substantial amount of space that can be used for the advertising of various products, to the end that the net cost of the bottle, to a dairy, can be substantially reduced and be made much less than the net cost of each use of glass bottles.

Other and more specific objects will be apparent from the following description taken in connection with the accompanying drawings, wherein—

Figure 1 is a plan view showing a blank from which my bottle is formed; in the drawings the solid lines represent actual margins whereas the dashed lines represent folding lines.

Figure 2 is a typical cross-sectional view through my bottle, when the same is assembled, showing the manner of forming the side seal.

Figures 3, 4, 5, and 6 show successive foldings of the bottom members to form my laminated bottom structure.

Figures 7, 8, 9, and 10 show successive steps in the forming of my bottle top and closure therefor.

Figure 11 is a fragmentary elevational view showing the inside of my milk bottle illustrating the means used in reinforcing the cream line window.

Figure 12 is a fragmentary view showing the form of my top opening for filling and pouring with the reinforcing and closing member therefor.

Figure 13 is a perspective view showing a preferred form in which the extreme end of my closure member is folded back to reinforce the same.

Figure 14 is a perspective view showing my milk bottle in its completed form.

Figure 15 is a fragmentary section in elevation showing the detail of my carrying or supporting bail member.

Figure 16 is a fragmentary, perspective view, partly in section, showing in detail the construction of the top, the closure member, and the cream-line window arrangement.

Referring to the drawings, throughout which like reference characters indicate like parts, numeral 16 generally designates the blank from which my bottle is formed. This blank is die-cut from a single piece of paper, with all the parts going into the construction of the finished bottle joined together along, at least, one full side, so that there are no small parts that may be lost or torn off. Each of the four sides is

formed as a truncated triangle so that when the bottle is formed it has the shape of a frustum of a pyramid. The proportions should be made to suit the commodities used. It is desired to point out that my container may be used for any granular product, for cereals, or for various liquids other than milk, such as fruit, or vegetable, juice, syrup, honey, catsup and many other such products.

10 In the present arrangement however I have found it desirable to retain in general the principal dimensions of the standard milk bottle as the trade is already equipped with many handling and filling devices, and transportation cases, normally provided with square partitions, so that if the general proportions of a two inch square top, a four inch square bottom and a nine inch height are maintained my present bottle can be used in much of the equipment that is 15 now used for quart milk bottles. In the same way a suitable reduction in size would make it convenient for use in the handling equipment of the smaller size milk and cream bottles.

The four sides as 18, 19, 20, and 21 are scored 25 as at 18a, 19a, 20a, and 21a, so that they will naturally fold on these folding lines. One side as 18 is provided with an extension on one of its sides to provide the sealing flap 22 which is used to seal the body of the bottle after the 30 showing in Figure 2 in which flap 22 is normally disposed inside the bottle with side 21 overlapping the same, the two being joined together with a suitable adhesive.

Each of the sides has an extension bottom 35 member attached to its lower end as 24, 25, 26, and 27. These are separated by the cut occurring at 24a, 25a, 26a; between the sides and the bottom portions are narrow, bead-forming portions as 29, 30, 31, and 32. Each of these 40 bead portions is provided with the scored folding lines as 34 and 35 and have their ends cut so that folding lines 34 are longer than folding lines 35 for a purpose that will be more clearly brought out later in the folding operation. Each 45 of the bottom-forming members is provided with folding lines as 36 and 37 so as to form the edge sealing members as 40, 41, 42, 43, 44, 45, 46, and 47.

Secured to the upper end of side members 18, 50 19, 20, and 21 are tab members 50, 51, 52, and 53. Tabs 51 and 53 join their respective sides 19 and 21 by the scored folding lines 54. Tabs 50 and 52 provide the carrying or supporting handle for the bottle.

55 In tab 51 and side 19, are struck-out mating openings as 56 and 57 which are disposed equidistant from folding line 54.

Tab 53 is arranged to form the top closure of the bottle. It consists of the top closure 60 member proper 60 which is pierced for the rectangular filling and discharge opening 61 and has side sealing tabs 62 and 63 each of which is provided with a scored folding line which separates it from the top member 60 proper. Midway in tab 53 occur three scored, folding lines 65, 66, and 67. The remainder of tab 53 is the top reinforcing portion 70. This member is provided of a size substantially equal to member 60 proper and arranged with an embossed or 70 press-formed indentation 72 of such a size as to wedge firmly into opening 61 so as to provide a sealing closure therefor. For certain purposes it has been found desirable to provide that tab 53 be provided with a further extension. This 75 is illustrated in detail in Figure 13 wherein a

tab extension, shown in dashed line at 74, is provided which will fold back into depression 72 and reinforce the same as shown in Figure 9 and Figure 13, forming the reinforcement member 75.

Forming the bottle

When it is desired to use my bottle the first operation, shown in Figure 8, is to place a suitable piece of transparent material 80 over opening 57 on the inside surface of the bottle blank allowing it to extend well over the margins after the showing in the dashed line in Figure 11. Tab 51 is then bent inwardly on folding line 54 and is secured, with opening 56 in registry with opening 57, to side 19 by a suitable adhesive and thus provides a secure frame for the transparent material forming the inspection or cream-line window.

The next operation is to fold the paper blank 20 along the lines 18a, 19a, 20a, and 21a, and tab 22 is secured by a suitable adhesive to side 21, after the showing of Figure 2. The bottom is 25 preferably formed next. This is accomplished by folding tab 24 upwardly into the base of the bottle, folding the same along the scored lines 34 and 35 so that bead portion 29 is against side 18 after the showing of Figure 3. Tab 24 is placed in a horizontal position and edge sealing members 40 and 41 then assume the position 30 shown in Figure 3, where they and member 28 are suitably secured to the side members preferably by a waterproof adhesive. In a like manner the other tab members, 25, 26, and 27 are secured in place after the showing of Figures 35 4, 5, and 6. When finished, as in Figure 6, it will be observed that a very strong bead is provided with a bottom of laminated structure giving four thicknesses of material. This provides a stiff, form-retaining wall, across the large end 40 of the bottle and serves as a base or bottom.

The top closure is made after the showing of Figures 7, 8, 9, 10, and Figure 11. Figure 7 shows the end members in the position it will assume when the sides are glued together and the bottom 45 in place.

In Figure 9 pad 53 has been bent along folding line 54 and brought across the top of the bottle. It is then folded on line 67 and back again on itself on line 66. This gives a bearing portion which can be secured to side 19 by a suitable adhesive. The tab is again folded along 65 so as to leave the closure member disposed somewhat above the filling, or pouring opening 61. The bottle is now in position for filling and after filling has been 55 accomplished indentation 72 is seated within opening 61 after the showing of Figure 10.

As soon as the bottle has been filled tabs 50 and 52 are overlapped after the showing of Figures 14 and 16 and joined by some suitable adhesive or by stapling at 82. The bottle or container of course 60 may be made of any suitable material. At present the material which seems most practical is an impregnated paper so calendered or finished that it will form a good base for paraffin treatment of the inside of the bottle. If the bottle is to be used for liquids the inside should be paraffined and preferably just before the bottle is filled so that the sterilizing qualities of the paraffin can be utilized to the fullest and any bacteria or the like which may have accumulated on the surface of the paper will be covered by this paraffin coating which in addition to performing the functions of waterproofing and sterilizing the bottle also acts as a sealing agent to fully seal all the folded seams wherein leaks might otherwise result.

It will be apparent, it is believed, that tabs 50 and 52 when they are cemented or stapled together form a very convenient carrying handle and also provide a bail which can be used for suspending the container from a doorknob, hook, or the like, and thus keep the package away from many sources of contamination, especially from animals.

The foregoing description and the accompanying drawings are believed to clearly disclose a preferred embodiment of my invention but it will be understood that this disclosure is merely illustrative and that such changes in the invention may be made as are fairly within the scope and spirit of the following claims:

Having thus fully described my invention, what I claim as new and desire to secure by Letters Patent is:

1. A folded blank for a container comprising a series of body portions each having a lower extension, said extensions adapted to form a laminated bottom; one of said portions having an opening therethrough, a transparent covering for said opening, and an upper extension having an opening aligned with said body opening; another of said body portions having an upper extension adapted to form a closure, and integral means forming a handle.
2. A folded blank for a container comprising a series of trapezoidal body portions each having a lower extension, said extensions adapted to form a laminated bottom; one of said body portions having an opening therethrough, a transparent covering for said opening, and an upper extension having an opening aligned with said body opening; another of said body portions having an upper extension adapted to form a closure, and integral means forming a handle.
3. A folded blank for a container comprising a series of trapezoidal body portions each having a lower extension, said extensions adapted to form a

laminated bottom; one of said body portions having an opening therethrough, a transparent covering for said opening, and an upper extension having an opening aligned with said body opening; another of said body portions having an upper extension adapted to form a closure, and a pair of other body portions each having an upper extension adapted to form a handle.

4. A folded blank for a container comprising a series of tapered body portions, each said body portions having a lower rectangular extension, said extensions having foldable adhering flanges and forming a laminated bottom; one of said body portions having an opening therethrough, a transparent covering for said opening, and an upper extension having an opening adapted for alignment with said body opening; another of said body portions having an upper extension adapted to form a closure, and means integral with two other body portions forming a handle.

5. A folded blank for a container comprising a series of body portions, one of the end portions having a longitudinal sealing flap adapted to overlap and join the end of the body portion; each body portion having a lower extension, said extensions adapted to form a laminated bottom; and one of said body portions having an upper extension provided with an opening therethrough adjacent one end and a closure for said opening adjacent the other end, said extension adapted to be folded intermediate said opening and said closure.

6. A folded blank for a container comprising a series of body portions each having a lower extension, said extensions adapted to form a laminated bottom, one of said body portions having an upper extension provided with a filling opening therethrough adjacent one end and a closure for said opening adjacent the other end, said extension adapted to be folded intermediate said opening and said closure.

HERALD T. SNYDER.
